UNITED STATES PATENT OFFICE.

JOHN LAWRENCE BALLARD, OF DENVER, COLORADO.

TYPEWRITING-MACHINE ATTACHMENT.

Application filed August 22, 1925. Serial No. 51,829.

This invention relates to typewriting machine attachments, and the particular improvements reside in a novel combination and assembly of means adapted for use in 5 connection with tabulating work.

The primary object of the invention has been to embody such means in the form of a simple and comparatively inexpensive adapter device, the elements of which are 10 directly associated in unitary assembly or in self-contained relation as it were, for facilitating predetermining and indicating the appropriate positioning or setting of the tabulator stops on the tabulator rack bar 15 of typewriting machines, whether of the decimal tabulating, key-set tabulating, or analogous types, in preparation for and in advance of actual statistical or form writing of various kinds, where figures are to 20 be disposed in vertical columnar arrangement across the writing surface of a page and with predetermined spacing between the columns.

The foregoing and other objects and advantages, however, as well as the manner of accomplishing the same, will be clearly apparent as incidental to the following disclosure, it is believed, so that with these 25 general outlining remarks, and without initial distinguishing over the prior art which is well understood, reference will be immediately had to the accompanying drawings, illustrating a practical embodiment of the improvements, in which drawings:

Figure 1 is a perspective view of the improved adapter device, fully assembled and in its preferred form as now employed, although susceptible of alterations within the scope of the broader invention; Figure 2 30 is a transverse sectional view along the line 2—2 of Figure 1; Figure 3 is a detached plan view of a main indicator element that is adapted for adjustment longitudinally of the device; Figure 4 is an analogous view 35 of an auxiliary indicator element, also functioning as a tabulator stop setting position finder, associated with said main indicator element in conjoint and independent adjustable relation therewith; Figure 5 is a fragmentary top plan view of a typewriting machine, such as the commercially known Underwood machine, showing the improved device in detachably fixed relation, on the carriage of the machine, relatively to the scale 40 pointer of the machine, with the main indicator element set to indicate a column of

figures starting in the tens of thousands, and with the auxiliary indicator element set to indicate a distance of four spaces between columns; Figure 6 is an analogous view to 45 Figure 5, but with the carriage of the machine shifted towards the extreme left end of the machine, and with a pointer on the auxiliary indicator element located at a predetermined position, dependent upon the margin to be left at the right side of the page to be written on; Figure 7 is a view analogous to Figure 6, but with the carriage and adapter shifted five spaces further to the left, of one space more than the indicated 50 desired space between columns; Figure 8 is a view analogous to Figure 7, but with the carriage and adapter shifted to the right, so that the pointer on the auxiliary indicator element will be opposite the graduation on the typewriter scale where the scale pointer of the machine was previously positioned in Figure 7; Figure 9 is a view analogous to Figure 8, but with the carriage 55 shifted to the right in a manner 60 analogous to that stated with reference to Figure 8; and Figure 10 is a plan view of a portion of a sheet of paper, illustrating a tabular arrangement of numerical columns.

With the style of typewriting machine partially illustrated, at Figures 5 to 9 of the drawings, the same is provided with a scale bar 11, having graduations 12 reading from right to left, which scale bar is attached to the upper forward framework 13 of the machine, in fixed relation therewith and in association with a movable index pointer 15 fixedly centered on a forward longitudinally disposed bar 14 of the platen carriage of the machine, so that the pointer 65 will be operated along said scale.

As my improved attachment in its preferred form, and as actually illustrated in the drawings, is more especially adapted for attachment to said platen carriage bar of such a type of machine, at the left of said machine index pointer, it will be so described in such relation only, for the sake of simplicity of illustration and brevity of description. It is to be understood at the outset, however, that such disclosure is not intended as a limitation to the general scope and uses of the actual invention, because the broader principles thereof may obviously be practiced with other styles of typewriting machines, and even with those having mov-

able or carriage supported scale bars, by an equivalently functioning transposition of the parts of the device and the positioning of the same relatively to any particular one of various styles of typewriting machines, with which the device is susceptible of use.

In the device as illustrated, the adapter may embody a T-shaped element, or body support, having a lateral forward base web or bar 16 and a rearwardly projected web or arm 17, the forward edge face portion of the web 16 being provided with an upturned marginal flange 18, extending longitudinally thereof, which is preferably headed or beaded, as at 19, and the outer end of the arm 17 being provided with means for attaching the device to the aforesaid carriage bar 14, or other suitable part 20 of the typewriting machine, although the actual manner of supporting the base bar 16 is not necessarily an essential part of the improvements and may obviously be varied.

25 A convenient means for this attachment, however, is shown as embodying an adjustably carried clamping member having a longitudinal web 20, a depending outer web 21 and an inner hook or downwardly projected inturned claw member 22, the clamping member being adapted for encompassing the carriage bar 14 in a manner that is clearly apparent from Figures 5 to 9. The web 20 carries an adjusting binding screw 23, extending through a slot 24 in said arm 17, and the depending web 21 carries a suitable set screw 25, preferably having a winged head and a loosely mounted engaging member, the whole clamp member providing for 30 limited adjustable mounting of the base bar 16, which may be desirable in attaching the adapter device in properly positioned relation to the scale bar 11 of different typewriting machines.

45 On the upper face of the base bar 16 there is disposed a scale member 26, shown as having thereon a digital key scale which for convenience of designation I shall refer to as a main adapter scale, and which is illustrated as designating the numerical value of hundreds of billions, written thus 100,000,000,000.00, preferably being appropriately divided off by commas and the usual decimal mark. However, the commas and 50 decimal mark may or may not be employed, and the scale may obviously indicate other numerical values, than actually shown, or even be for other tabular designations; but it is essential that the graduations thereof be equidistantly spaced to correspond with the spacing of the graduations of the scale 12 of the typewriting machine, whether the latter scale is graduated for pica type, elite type, or otherwise.

60 65 For the foregoing and other reasons,

therefore, the main adapter scale 26 is preferably mounted as a detachable member or slide, so that one form of scale may be substituted for by another with the same adapter device, and this may be provided for by the employment of end guide members 27, inturned and spaced from the base web 16, which are closed at their lower ends and open at their upper ends.

The base bar 16 is preferably provided with a forwardly projected pointer 28, or its equivalent, located towards one end thereof, which may be conveniently referred to as the adapter positioning indicator, as it aids in determining the correct positioning of the adapter relatively to the machine carriage indicator 15, as will later appear, and in mounting the adapter scale 26, on its base bar support 16, the last character or naught of the scale 26 is disposed in registration with said pointer 28.

Slidably associated with said main adapter scale 26, which functions as a column value or width indicating scale as will later appear, is an adjustable main rider or indicator element 29, see Figure 3, which carries a machine scale pointer 30 or its equivalent, towards one end thereof, and which pointer 30 may be conveniently referred to as a decimal indicator, as it determines the position for setting a decimal tabulator stop, if desired, on the tabulator rack bar of the typewriting machine, as will also later appear, and also functions as a visual indicator of the position where the decimal should be located, even when writing with other styles of typewriters than actual decimal tabulating machines. The said main rider or slide 30 also carries a main adapter scale pointer 31, or its equivalent, disposed in a direction opposite to said decimal pointer 30 and located inwardly four scale graduations or spaces distant therefrom, which main adapter scale pointer 31 may also be designated as a column width or value indicator, as it shows the position of the first character in a maximum line of a column of predetermined width, indicated in the drawings at the right side of Figure 10, and in Figures 5 to 9, as a column of the normal maximum value of tens of thousands. The upper surface of this main rider element 29 is preferably provided with an auxiliary adapter scale 32 embodying numerals 1, 2, 3, 4 etc., in consecutive order and equidistantly spaced to correspond with the graduations of the other mentioned scales, with the numeral 1 thereof located in registration with the decimal indicator 30, and hence with the column value indicator 31 disposed opposite to the position of the auxiliary scale numeral 5. This auxiliary adapter scale 32 may also be conveniently designated as a column spacing indicator scale, because the highest number exposed thereon will in-

dicate the number of spaces between columns, for which the adapter is set and as controlled by an auxiliary rider element now to be described.

- 5 This auxiliary indicator or rider element is shown detached, at Figure 4, as well as in its operative positions in the assembly views of the drawings. It embodies a slide member or body portion 35 of short length, 70 for mounting upon and longitudinal adjustment along said main rider 29, being provided with a pointer 36 or its equivalent, towards one end thereof, disposed for association with the scale 12 of the typewriting machine. The pointer 36 is located three and one-half spaces or graduations distant from the other end of the body portion 35, which latter end is adapted for exposing the desired number on the column spacing indicator scale 32, with the succeeding higher numbers thereof covered up. Although this auxiliary rider's pointer 36 functions in additional relations under some conditions, as will later appear, in the preferred adaptation as illustrated it is essentially employed as a guide indicator for positioning the carriage, in the shiftings of the latter to the right for determining the positions for setting the tabulator stops on the tabulator 75 rack bar. In other words the pointer 36, in the aforesaid shiftings of the carriage after the first shifting to the right, is always conjointly moved with the carriage to the preceding position last occupied by the carriage pointer 15, and hence this auxiliary rider pointer 36, or its equivalent, may also be conveniently referred to as a carriage positioning guide indicator, for a more definite designation of the same.
- 40 Both of the rider elements 29 and 35 could be of flatwise formation or of other cross-sectional structure than as actually shown, but when the upturned flange 18 is employed, as the mounting therefor, these 80 rider members are preferably formed of springy metal and of substantially circular shape in cross-section, somewhat like an open-ended tube with a longitudinally slotted or slightly open bottom periphery. Thus 85 the main rider 29 is adapted to clasp over the beaded upturned flange or front wall 18, in gripping sliding relation therewith, and the auxiliary rider 35 is adapted to clasp over the main rider 29, in gripping sliding relation, so that the auxiliary rider 35 is 90 longitudinally adjustable both conjointly with and also independently of the longitudinally adjustable main rider 29, and either or both of these rider members may 95 obviously be provided with indented depressions or slight projections, if desired, to aid in the adjusting actuations of the same.
- 60 In describing the operations of the improvements with particular reference to the 100 style of typewriting machine partially illustrated, being a No. 5 Underwood machine, and the same in general principle will be true with other types of machines, the adapter device as a whole is attached to the carriage bar 14, with the adapter positioning indicator 28 located two spaces or scale graduations to the left of the machine carriage pointer 15.
- Now, assuming that it is desired to tabulate, across the writing surface of the paper to be written on, in columns of a normal maximum line width of the numerical values of tens of thousands, the same being punctuated with segregating commas and decimal 105 mark or otherwise in accordance with the adapter scale 26, with four spaces or scale graduations between columns, and with the last character of the last column to be located at the machine scale graduation 80, as 110 is illustrated by the three columns at the right of Figure 10, the operations would then be as follows:—
- The riders 29 and 35 should first be adjusted so that the column value indicator 31, 115 of the main rider 29, would be opposite the digit representing tens of thousands on the main adapter scale 26, and with the auxiliary rider 35 uncovering the numeral 4 on the auxiliary or column spacing indicator scale 120 32. This being done, the platen carriage is then first shifted towards the extreme left of the machine until the pointer 36, of the auxiliary rider 35, is opposite the machine scale graduation 80, as illustrated at Figure 125 100, or for that matter to any other of the machine scale graduations indicating where the last character of the last column of the typewritten page is to appear. In the given illustration, therefore, the machine pointer 130 105 110 115 120 125 130 135 140 145 150 155 160 165 170 175 180 185 190 195 200 205 210 215 220 225 230 235 240 245 250 255 260 265 270 an appropriate tabulator stop or stops, as desired, may be accordingly set on the scale graduated tabulator rack bar, of the typewriting machine, for controlling the tabular writing for said last column.

Now, in order to locate the positioning of the tabulator stops for the next column to the left, or the second column from the right of the sheet, under the same example and with four spaces between columns, the platen carriage is simply shifted to the right until the carriage positioning guide indicator 36, of the auxiliary rider 35, is opposite the machine scale graduation 72, which is the last preceding graduation at which the machine pointer 15 was positioned, when as illustrated at Figure 8 the carriage pointer 15 will then be opposite the scale graduation 59, with the decimal indicator 30 in registration with the scale graduation 65. The pointer 15 will therefore indicate the scale graduation 59, as the position on the tabulator rack bar to set a stop for starting said second column, whereas the indicator 30 will show the position for setting a decimal stop at 65 on the rack bar, if desired, so that the last character of the line of that second column will be positioned at the graduation 67, with four spaces between it and the beginning of the last column at 72. In an analogous manner to that just described, the carriage is again shifted to the right, for indicating the third column setting, until the pointer 36 of the auxiliary rider is opposite to the machine scale graduation 59, as shown at Figure 9, when the machine pointer 15 will be opposite the scale graduation 46, indicating the starting point of the third column, and the pointer 30, or decimal indicator, of the main rider 29 will be opposite the scale graduation 52, indicating the decimal position of said third column.

These operations are repeated for as many columns as are to appear on the sheet and of the numerical valuations of tens of thousands, with four spaces between columns, but in the fourth column, from the right of Figure 10, the numerical value is indicated as being in the hundreds of thousands, with only three spaces between the third and fourth columns from the right. In figuring that adjustment, therefore, the main rider 29 is first shifted to the left until its pointer 31 registers with the digit, of the main adapter scale 26, representing hundreds of thousands, and the auxiliary rider 35 is shifted to the right, on the main rider, to cover the numeral 4 on the auxiliary adapter scale 32, leaving the numeral 3 as the highest one exposed, which will indicate three spaces between columns. The carriage is then shifted to the right as heretofore, for indicating the positions for setting appropriate tabulator stops. So also, in figuring the set-

tings for the extreme left column, of Figure 10, indicating a columnar value line of millions with two spaces between columns, an analogous procedure is followed, as will be obvious.

With decimal tabulating typewriting machines proper, it is only necessary, strictly speaking, to set a tabulator stop, on the tabulator rack bar, for the decimal position, whether said tabulator stop is set manually or is key-set, although the tabulator stops may be set for the beginning of columns instead of the decimal positions, and as a matter of fact this is frequently done by many operators. With typewriting machines not of the decimal tabulating type, however, but which have a tabulator rack bar, it is then necessary to set the tabulator stops for the beginning of the columns. With such latter types of machines, therefore, my adapter device does not necessarily have to have the decimal indicator 30, and also by the employment of the decimal indicator 30 it may not be strictly essential to have the auxiliary scale 32, because it may readily be determined how many spaces are provided for between columns, by noting the number of spaces between the pointers 30 and 31. However, the inclusion of all of these features is extremely desirable in aiding the eye, as well as for the better adaptation of the improved device for use with various types of machines, and it may also be said that the device itself is very practicable for visual indications even when used with machines that do not have tabulator rack bars.

When the pointer 36, of the auxiliary rider 35, is set oppositely of the pointer 31 of the main rider 29, in addition to its primary functioning, as a carriage positioning guide element, it will also in that particular position indicate the position of the first digit of the columns, when only one space is to be left between columns, which is frequently the case.

Finally, while I have more particularly described the improvements for use in connection with the tabulation of columns of numbers, having segregating commas and decimal mark, it is to be understood, as hereinbefore expressed, that the improved device is likewise fully adapted for use in connection with the tabulation of columns of figures not necessarily having punctuation marks, as well as in column form writing generally, whether in numbers, words or otherwise, but in those events, of course, the main adapter scale 26 would be of appropriately altered form, than that actually shown in the drawings, in conformity with the class of columnar tabulation to be done.

Having thus fully set forth the invention from various angles, it will nevertheless be understood that I do not restrict myself

to all details exactly as disclosed, excepting as they may come within the terms of the claims, or their equivalent, or as fairly interpreted in the light of the specification if necessary, as some changes may obviously be made without departing from the spirit of the invention.

What I do claim, however, as new and patentable, is:—

- 10 1. In typewriting machine attachments of the character disclosed, embodying an adapter with a scale thereon graduated to conform with the scale of the typewriting machine, and an adjustably mounted indicator member carrying a plurality of indicator means, one of which said indicator means is associated with said adapter scale, while another of which is adapted for association with said machine scale in separately adjustable relation therewith and with said adapter scale indicator means.
- 15 2. In typewriting machine attachments of the character disclosed, embodying an adapter with a scale thereon graduated to conform with the scale of the typewriting machine, and an adjustably mounted indicator member carrying a plurality of indicator means, one of which said indicator means is associated with said adapter scale, another of which is adapted for association with said machine scale, as a decimal indicator, in fixed relation to said adapter scale indicator means, while another of which is adapted for association with said
- 20 3. In typewriting machine attachments of the character disclosed, embodying an adapter with a scale thereon graduated to conform with the scale of the typewriting machine, and an adjustably mounted indicator member carrying a plurality of indicator means, one of which said indicator means is associated with said adapter scale, another of which is adapted for association with said machine scale in separately adjustable relation therewith and with said other scale indicator means.
- 25 4. In typewriting machine attachments of the character disclosed, embodying an adapter support with a scale thereon graduated to conform with the scale of the typewriting machine, a main rider mounted for longitudinal adjustment along said support and carrying indicator means associated with said adapter scale, and an auxiliary rider mounted on said main rider for longitudinal adjustment therealong and carrying indicator means adapted for association with said machine scale.
- 30 5. In typewriting machine attachments of the character disclosed, embodying an adapter support with a scale thereon graduated to conform with the scale of the typewriting machine, a main rider mounted for longitudinal adjustment along said support, which main rider has indicator means, associated with said adapter scale, and also has an auxiliary adapter scale thereon graduated to conform with said other scales, and an auxiliary rider mounted on said main rider for longitudinal adjustment therealong, in column spacing indicating association with said auxiliary scale, and carrying indicator means adapted for association with said machine scale.
- 35 6. In typewriting machine attachments of the character disclosed, embodying an adapter support with a main adapter scale thereon graduated to conform with the scale of the typewriting machine, a main rider mounted for longitudinal adjustment along said support, which main rider carries indicator means associated with said main adapter scale, has an auxiliary adapter scale thereon, graduated to conform with said other scales, and also carries indicator means adapted for association with said machine scale, as a decimal indicator, in fixed relation to said main adapter scale indicating means and four scale graduations distant therefrom, and an auxiliary rider mounted on said main rider for longitudinal adjustment therealong, in column spacing indicating association with said auxiliary scale, and carrying indicator means adapted for association with said machine scale.

writing machine, a main rider mounted for longitudinal adjustment along said support, 55 which main rider carries indicator means associated with said adapter scale and also carries indicator means adapted for association with said machine scale, as a decimal indicator, in fixed relation to said adapter 60 scale indicating means and four scale graduations distant therefrom, and an auxiliary rider mounted on said main rider for longitudinal adjustment therealong and carrying indicator means adapted for association 65 with said machine scale.

5. In a typewriting machine attachments of the character disclosed, embodying an adapter support with a main adapter scale thereon graduated to conform with the scale 70 of the typewriting machine, a main rider mounted for longitudinal adjustment along said support, which main rider has indicator means, associated with said adapter scale, and also has an auxiliary adapter scale 75 thereon graduated to conform with said other scales, and an auxiliary rider mounted on said main rider for longitudinal adjustment therealong, in column spacing indicating association with said auxiliary scale, and carrying indicator means adapted for association with said machine scale.

6. In typewriting machine attachments of the character disclosed, embodying an adapter support with a main adapter scale 85 thereon graduated to conform with the scale of the typewriting machine, a main rider mounted for longitudinal adjustment along said support, which main rider carries indicator means associated with said main 90 adapter scale, has an auxiliary adapter scale thereon, graduated to conform with said other scales, and also carries indicator means adapted for association with said machine scale, as a decimal indicator, in fixed relation to said main adapter scale indicating means and four scale graduations distant therefrom, and an auxiliary rider mounted on said main rider for longitudinal adjustment therealong, in column spacing 100 indicating association with said auxiliary scale, and carrying indicator means adapted for association with said machine scale.

In testimony whereof, I affix my signature.

JOHN LAWRENCE BALLARD.
